HYDROCARBON CONVERSION

Herbert J. Passino, Englewood, N. J., assignor to
The M. W. Kellogg Company, Jersey City, N. J.,
a corporation of Delaware

Application March 14, 1942, Serial No. 434,734

16 Claims. (Cl. 260—671)

This invention relates to the production of alkylated aromatic hydrocarbons. More particularly, the invention relates to the production of alkylated hydrocarbons by reaction of aromatic hydrocarbons of higher molecular weight, such as more highly alkylated aromatic hydrocarbons, in the presence of a catalyst essentially comprising hydrogen fluoride and boron fluoride. Still more particularly, the reaction relates to the production of alkylated aromatic hydrocarbons by 10 the reaction of more highly alkylated aromatic hydrocarbons and aromatic hydrocarbons alkylated to a lesser degree in the presence of a catalyst essentially comprising hydrogen fluoride and boron fluoride. The subject matter of this application is disclosed in part in prior application Ser. No. 395,973, filed May 31, 1941.

The production of the desired alkylated aromatic hydrocarbons in accordance with the process of this invention apparently occurs as a result of simultaneous dealkylation of the aromatic hydrocarbons of higher molecular weight, such as more highly alkylated aromatic hydrocarbons, by the removal of alkyl groups therefrom and alkylation of the aromatic hydrocarbons previously alkylated to a lesser degree than the desired aromatic hydrocarbons, by means of the alkyl groups formed by the dealkylation reactions.

While the process of the invention is applicable to the treatment of mixtures of hydrocarbons to obtain a product consisting of a mixture of desired alkylated hydrocarbons, it will be described for purposes of clarity by reference to the production of a single alkylated aromatic hydrocarbon from aromatic hydrocarbons alkylated to a lesser degree and higher molecular weight aromatic hydrocarbons such as more highly alkylated aromatic hydrocarbons. For example, the production of toluene by the reaction of benzene and xylene will be referred to specifically in the further description of the invention. Other specific examples are the production of xylenes through the reaction of toluene and trimethyl benzene. The invention is not limited, however, to the production of methylated aromatic hydrocarbons, but includes also the production of alkylated hydrocarbons by reactions of ethylated hydrocarbons with hydrocarbons alkylated to a lesser degree, such as the reaction of benzene with diethyl benzene. The invention includes within its scope also reactions in which alkylated aromatic hydrocarbons having relatively long alkyl side chains or which have attached rings are dealkylated by the formation, from such side chains or attached rings, of alkyl groups having

5 a lesser number of carbon atoms which thereupon alkylate the aromatic hydrocarbon previously alkylated to a lesser degree than the desired alkylated aromatic hydrocarbon.

In the further description of the invention reference will be made specifically to the reaction of xylenes with benzene to produce toluene because toluene is highly important as an ingredient of motor fuels of high octane value and as a starting material in the preparation of other valuable materials, such as explosives. The reaction of xylenes with benzene to produce toluene provides an excellent example of this process in view of the extreme difficulty in which this reaction is 15 effected by previously known methods as compared to other similar reactions such as the reaction of benzene with diethyl benzene.

The reaction of xylenes and benzene to produce toluene is carried out preferably in the liquid phase in the presence of a catalyst essentially comprising substantial amounts of boron trifluoride and hydrogen fluoride. While the boron trifluoride and the hydrogen fluoride need not be present in the reaction zone in the form of a physical mixture, it is necessary that they be available for simultaneous contact with the hydrocarbons undergoing reaction treatment whereby they function essentially as a single catalytic material. While the relative proportions of the 20 hydrogen fluoride and boron trifluoride may vary within a considerable range, it is necessary that the hydrogen fluoride be present in the reaction zone in a substantial quantity in relation to the proportion of hydrocarbon reactants present. This constituent of the catalytic material should be present in the reaction zone in an amount 25 equivalent to over 5 weight per cent of the hydrocarbon reactants present and preferably in an amount equivalent to at least 10 weight per cent of the hydrocarbon reactants present. The quantity of boron fluoride in contact with the hydrocarbon reactants and hydrogen fluoride relative to the quantity of hydrocarbon reactants may 30 vary within relatively wide limits but ordinarily should be equivalent to approximately 5 to 25 weight per cent of the hydrocarbon reactants. Conveniently, both the hydrogen fluoride and boron fluoride contacting the hydrocarbons are present in amounts equivalent to 5 to 25 weight 35 per cent of the hydrocarbon reactants present.

Ordinarily, it is desirable to maintain the reaction conditions such that the hydrocarbons and catalytic materials are substantially in the liquid phase. Alternatively, the hydrocarbons may be 40 maintained in the liquid phase and the catalytic

material contacted therewith while one or both are in the vapor phase. The most favorable operating conditions appear to be approximately 200° to 400° F. and 300 to 1000 pounds per square inch. The reaction time necessarily is the length of time required to effect the desired reaction under the operating conditions selected. The reaction time depends a great deal upon the intimacy of contact between the catalytic materials and the hydrocarbon reactants. Conveniently, the reaction is carried out in the liquid phase, and the mixture of reactants and catalyst is beaten or stirred into an emulsion in which the desired intimate contact is effected. Conveniently, the reaction is carried out in a continuous manner in which a portion of a body of the emulsion of reactants is continuously withdrawn and replaced with fresh supplies of hydrocarbon reactants and catalyst. The hydrocarbons withdrawn are fractionated to separate the desired alkylate product and other fractions suitable for recycling.

Preferably, the hydrocarbon reactant which is alkylated to a lesser degree, in this instance benzene, is maintained in the reaction zone in considerable excess of the amount required to react with all of the more highly alkylated aromatic hydrocarbon reactant in order to promote formation of the desired alkylate product. For example, in the reaction of benzene with xylenes it is desirable to maintain the benzene in the reaction zone in considerable excess of the amount required to react with all the xylene to form toluene. A molar ratio of benzene to xylene of at least 2:1 is desirable, and it is preferred that this ratio be 4:1 or higher.

Example I

A reaction mixture consisting of approximately 529 parts by weight of benzene and 175 parts by weight of xylenes was intimately contacted with a catalyst consisting of 100 parts by weight of hydrogen fluoride and 50 parts by weight of boron fluoride. The mixture of hydrocarbons and catalyst was contacted under a pressure of 650 pounds per square inch at a temperature of 300° F. for a period of approximately 3 hours. The hydrocarbons were thereafter separated from the catalyst and upon analysis were found to comprise 21.3 volume per cent of toluene and 64.0 volume per cent of benzene, the remainder being hydrocarbons higher boiling than toluene and apparently consisting for the most part of xylenes. Since no light hydrocarbons were produced, the foregoing analysis indicates a production of toluene to the extent of 49.2 per cent of the theoretical maximum which could have been produced by reaction of all the xylenes in the mixture in accordance with the following reaction

The consumption of benzene was slightly more than the amount equivalent to the formation of the toluene by the above reaction, whereas the recovery of heavier materials including xylenes was slightly more than would be expected from the formation of the toluene by the above reaction. Apparently, a small amount of the benzene reacted directly with xylenes to form higher-boiling hydrocarbons such as anthracene which were included in the xylene fraction.

Example II

82 parts by weight of the xylene fraction recovered in Example I were mixed with 529 parts

5 by weight of benzene, 100 parts by weight of hydrogen fluoride and 50 parts by weight of boron fluoride and subjected to the same reaction conditions as described under Example I. The liquid product of this operation was analyzed and found to comprise approximately 6 volume per cent of toluene, 82 volume per cent of benzene and 12 volume per cent of material higher boiling than toluene and apparently including a substantial amount of unreacted xylenes. This production of toluene represents a yield of 25.5 per cent of the theoretical maximum yield which could be obtained from the xylene fraction if it consisted entirely of xylenes. This production of toluene probably represents a higher percentage of the theoretical maximum yield since it is probable that the xylene fraction was not entirely made up of xylenes. However, since such xylenes as were in the xylene fraction treated in this operation were materials unreacted in Example I, the total production of toluene in the two operations represents a yield equivalent to 61 per cent of the theoretical maximum yield of toluene obtainable by reacting all the xylenes present in accordance with the above reaction. This does not represent, however, the maximum yield obtainable since the heavy fraction recovered from Example II contained additional convertible xylenes and since the quantity of the xylene fraction employed in Example II did not represent the total amount of such a material recovered from the product of Example I.

35 Apparently the presence of both the hydrogen fluoride and boron fluoride was necessary to effect the production of toluene in the foregoing examples. For example, when 705 parts by weight of a hydrocarbon mixture consisting of 80 per cent benzene, 3 per cent toluene and 17 per cent xylenes was contacted with 120 parts by weight of hydrogen fluoride for 18 hours at 300° F., and 520 pounds per square inch pressure no additional toluene was produced. 702 parts by weight of a mixture of 50 per cent benzene, 7 per cent toluene and 43 per cent xylenes was treated at 400° F. and 940 pounds per square inch pressure in the presence of 150 parts by weight of hydrogen fluoride for a period of 5 hours without the production of additional toluene. 706 parts by weight of a hydrocarbon mixture consisting of 70 per cent benzene, 4 per cent toluene and 26 per cent xylenes was contacted for 8 hours at a temperature of 400° F. and a pressure of 1040 pounds per square inch with a catalyst consisting of 150 parts by weight of hydrogen fluoride and 20 parts by weight of nickel without the production of additional toluene. A hydrocarbon mixture similar to that treated in Example I was subjected to contact with a catalyst consisting of 100 parts of boron fluoride for a period of 3 hours at a temperature of 300° F. and a pressure of 690 pounds per square inch without the production of any toluene.

65 The invention will be described in more detail, in connection with the reaction of benzene and xylenes to produce toluene, by reference to the accompanying drawing which is a diagrammatic view in elevation of an arrangement of apparatus suitable for carrying out the invention. It is to be understood, however, that the reference to the specific reaction of benzene and xylenes and the reference to the specific apparatus illustrated in the drawing are illustrative only of certain modifications of the invention which is capable of other modifications.

70 Referring to the drawing, benzene, flowing

through line 1, xylenes flowing through line 2, and a mixture of hydrogen fluoride and boron fluoride, flowing through line 3, are introduced into a suitable mixer 4. From mixer 4 the resulting mixture of hydrocarbon reactants and catalyst is passed through line 5 to a suitable reactor 6. In reactor 6 the mixture of reactants and catalyst is subjected to agitation to effect intimate contact of hydrocarbon reactants with each other and with the catalyst for a sufficient length of time to effect the desired reaction. Agitation of the mixture may be effected by any suitable means for mixing or beating the mixture, or the mixture may be circulated continuously through a closed circuit including a plurality of jets located within the reaction zone to effect intimate mixing of the material circulated through the circuit and in the zone into which the circulated material is injected.

A portion of the mixture of reactants and catalyst maintained in reactor 6 is withdrawn therefrom continuously through line 7 which connects with a settler 8. In settler 8 the mixture is permitted to separate into an upper hydrocarbon layer and a lower hydrogen fluoride layer. Most of the boron fluoride remains absorbed in the hydrogen fluoride layer, although a portion is absorbed in the hydrocarbon layer, and a portion may separate as a gas. The latter portion of the boron fluoride may be recycled directly to the reaction zone by means of line 9 which connects the upper portion of settler 8 with line 3.

The lower liquid layer separated in settler 8 contains substantially all the hydrogen fluoride, a large proportion of the boron fluoride and includes also a complex of hydrogen fluoride and aromatic hydrocarbons. This layer of material is withdrawn from settler 8 through line 10 which connects with a second settler 11. Line 10 is provided with suitable heating means 12 whereby the mixture passing through line 10 is heated sufficiently to decompose the complex with the release of aromatic hydrocarbons and hydrogen fluoride. The hydrogen fluoride and boron fluoride are vaporized by the heat applied at 12 and separate in settler 11 from the remaining liquid. The mixture of hydrogen fluoride and boron fluoride vapors is recycled to the reaction zone from settler 11 through line 13 which connects settler 11 with line 3. The liquid in settler 11 separates into a lower layer of sludge which is withdrawn through line 14 and an upper layer comprising aromatic hydrocarbons released by the decomposition of the complex.

The hydrocarbon layer separated in settler 8 is transferred therefrom to fractionator 15 through line 16 by means of pump 17. The hydrocarbon layer separated in settler 11 is likewise transferred to fractionator 15 through line 18, provided with pump 19, which connects settler 11 with line 16.

In fractionator 15 the hydrocarbons introduced therein are subjected to fractionating conditions of temperature and pressure effective to separate the hydrocarbons into a light fraction essentially consisting of benzene which is withdrawn overhead, a heavy fraction essentially consisting of unreacted xylenes and higher-boiling hydrocarbons which accumulate in the bottom of fractionator 15, and an intermediate fraction essentially consisting of toluene which is withdrawn from fractionator 15 as a side cut through line 20. The benzene vapors are withdrawn overhead through line 21 which connects with cooling

means 22. At 22 the vapors are cooled sufficiently to effect complete condensation of the benzene, and condensate thus obtained, together with any uncondensed material such as boron fluoride, is transferred to reflux drum 23 through line 24. Benzene collected in drum 23 is withdrawn therefrom through line 25, provided with pump 26, and introduced into line 1 for recycling to the reaction zone. A portion of the benzene condensate may be diverted from line 25 through line 27 and returned to the upper portion of fractionator 15 as reflux. The boron fluoride separated in drum 23 is withdrawn through line 28. Suitably, this material may be returned to the reaction zone through line 29 which connects line 28 with line 3.

The condensate collected in the lower portion of fractionator 15 which includes unreacted xylene and higher-boiling hydrocarbons 20 is withdrawn therefrom through line 30 which connects fractionator 15 with line 2 whereby material passing therethrough is recycled to the reaction zone. If necessary all or a portion of the material passing through line 30 may be diverted through line 31 which connects with a settler 32. In settler 32 any sludge is permitted to settle out and is withdrawn through line 33. The remaining material thus free from sludge is returned to line 30 through line 34 which connects line 30 with the upper portion of separator 32.

Inasmuch as the reaction appears to form a small amount of hydrocarbons higher boiling than xylene, apparently through direct combination of benzene and xylene, it may be desirable to further fractionate the material passing through line 30 before reintroduction into the reaction zone to remove such high-boiling hydrocarbons and prevent the accumulation of these materials in the system. For example, all or a portion of the hydrocarbon flowing through line 30 is diverted through line 35 and introduced into a fractionator 36. In fractionator 36 conditions of temperature and pressure are maintained to separate overhead a vapor fraction essentially comprising xylenes and a heavy liquid fraction which collects in the lower portion of fractionator 36. This relatively high-boiling material, which may comprise hydrocarbons such as anthracene, etc., is withdrawn from fractionator 36 through line 37. A sufficient amount of such high-boiling material is withdrawn from the system in this manner to prevent its accumulation in the reaction zone. The high-boiling hydrocarbons withdrawn at 37 may be subjected to further treatment for the recovery of lower-boiling aromatic hydrocarbons therefrom. For example, by simple heat treatment of this material substantial quantities of toluene as well as other hydrocarbons are recovered.

The xylene vapors are withdrawn overhead in fractionator 36 through line 38 which connects to reflux drum 39. Line 38 is provided with cooling means 40 to effect complete condensation of the xylene vapors, and the resulting condensate accumulates in drum 39. A portion of this condensate is returned to the upper portion of fractionator 36 through line 41 as reflux, and the remainder is withdrawn through line 42 and introduced into line 30 for recycling to the reaction zone.

In the reactor 6 the ratio of benzene to xylenes is maintained as high as practical to minimize the formation of sludge and to accelerate the re-

action. In order to maintain a high ratio of benzene to xylene in reactor 6 it is necessary to maintain a high ratio of such materials in the mixture introduced through line 5 into the reactor 6. For example, a ratio of 4 parts by weight of benzene to 1 part by weight of xylene in the mixture introduced through line 5, or higher, is desirable to facilitate the reaction in the manner described. It is necessary, however, to supply to the system only the amount of benzene necessary to react with all the xylene since the excess of benzene is recovered for recycling through line 25.

The foregoing method for reacting benzene and xylenes is adapted to the treatment of such hydrocarbons obtained from any suitable source. The invention is, however, particularly adapted, especially in the reaction of benzene and xylenes, for use in connection with the catalytic aromatization treatment of aliphatic hydrocarbons containing the requisite number of carbon atoms per molecule wherein such aliphatic hydrocarbons are converted to aromatic hydrocarbons by dehydrogenation and cyclization reactions.

In accordance with this modification of the invention a hydrocarbon mixture, which may contain aromatic hydrocarbons but which also contains aliphatic and/or olefinic hydrocarbons having at least 6 to 8 carbon atoms per molecule, is introduced into the system through line 43 provided with pump 44. The hydrocarbon mixture thus introduced may be a relatively narrow fraction containing aliphatic hydrocarbons having 6 to 8 carbon atoms per molecule, or it may be a fraction having a relatively wide boiling range such as a heavy naphtha. Line 43 connects with the inlet of a heating coil housed in a suitable heater 45 wherein the hydrocarbon mixture is heated to a temperature of 850° F. to 1050° F., preferably 950° F. The outlet of the heating coil in heater 45 connects with line 46 by means of which the heated hydrocarbon mixture is introduced into reactor 47.

Reactor 47 is provided with a suitable catalytic material for effecting the desired aromatization reactions. Catalytic material suitable for this purpose includes the oxides of chromium and molybdenum, preferably mounted on a suitable support, such as alumina. Reactor 47 may be maintained at atmospheric or subatmospheric pressure, but preferably at superatmospheric pressure. During the passage of the hydrocarbons through reactor 47 aliphatic hydrocarbons having 6 to 8 or more carbon atoms per molecule are converted to corresponding aromatic hydrocarbons such as benzene, toluene, xylene and higher-boiling aromatic hydrocarbons by dehydrogenation and cyclization reactions. Hydrocarbons of this character which may be present in the hydrocarbon mixture introduced into reactor 47 apparently do not react to an appreciable extent in reactor 47 under the conditions described, and this treatment is therefore applicable to mixtures containing substantial proportions of aromatic hydrocarbons as well as to mixtures substantially free of aromatic hydrocarbons.

The degree of conversion of aliphatic hydrocarbons to aromatic hydrocarbons in reactor 47 is controlled by suitable regulations of temperature and space velocity. Substantial production of aromatic hydrocarbons is associated with high temperatures and relatively low space velocities. Within the temperature range mentioned space velocities of 0.1 to 3.0 volumes of liquid per volume of catalyst space per hour are employed advantageously. For example, at the preferred

operating temperature of 950° F. the space velocity of 0.5 volumes of liquid per volume of catalyst space per hour may be employed.

The reactants are withdrawn from reactor 47 through line 48 which connects with a separator 49. The reactants are cooled by passage through cooler 50 located in line 48 whereby the normally liquid constituents of the reaction mixture are condensed. The resulting mixture is separated in separator 49 into a gas which is withdrawn overhead through line 51 and a condensate which is withdrawn through line 52, provided with a pump 53.

The gas withdrawn through line 51 consists principally of hydrogen, and a portion thereof may be recycled through line 54, provided with a compressor 55, to line 43 in order to recycle hydrogen to the reaction mixture in the amount of 0.5 to 9, preferably 3.0 mols of hydrogen per mol of hydrocarbon reactants. The recycling of hydrogen in this manner is advantageous, particularly when reactor 48 is maintained under a hydrogen pressure of 30 to 450 pounds per square inch, in maintaining the activity of the catalyst in reactor 48.

The condensate withdrawn from separator 49 through line 52 is introduced into a fractionator 56. In fractionator 56 conditions of temperature and pressure are maintained to separate fractions concentrated in benzene, toluene and xylenes, respectively. A fraction concentrated in toluene and containing at most a minor proportion of other aromatic hydrocarbons is withdrawn as a side cut through line 57. This material may be treated in any suitable manner for extraction of toluene therefrom, for example, by extraction with phenol. The toluene fraction passing through line 57 may be introduced, after being heated to a suitable temperature at 58, into extractor 59. In extractor 59 the hydrocarbon mixture is passed upwardly in countercurrent contact with a downwardly moving stream of phenol which absorbs toluene from the hydrocarbon mixture. The extract containing the toluene is withdrawn through line 60 and introduced into stripper 61 for the regeneration of toluene therefrom. Toluene thus separated is withdrawn overhead through line 62 as a product of the process. Solvent stripped of toluene is withdrawn from stripper 61 through line 63 and reintroduced into the upper portion of extractor 59. The hydrocarbon mixture containing a substantially reduced concentration of aromatic hydrocarbons is withdrawn overhead in extractor 59 through line 64. Suitably this mixture is recycled to the aromatization process by a suitable connection of line 64 with line 43.

The hydrocarbon fraction concentrated in respect to benzene and containing at most a minor proportion of other aromatic hydrocarbons is withdrawn from the fractionator 56 as a side cut through line 65 for use in the reaction of benzene with xylenes. The xylene fraction may be obtained in the form of the bottoms from fractionator 56 which are withdrawn therefrom through line 66. This fraction contains a substantial proportion of xylenes and in addition some higher-boiling aromatic hydrocarbons such as poly methyl benzenes, etc. which are suitable for reaction with benzene to form toluene. Preferably, however, the xylenes are withdrawn from fractionator 56 as a side cut through line 67 in order to obtain a fraction relatively concentrated in xylenes and containing at most a minor proportion of other aromatic hydrocarbons. If desired a permissible proportion of the bottoms

may be included in the xylene fraction by means of line 68 which connects line 66 with line 67.

The material uncondensed in fractionator 56, which consists essentially of hydrocarbons lower boiling than benzene is withdrawn overhead through line 69. A portion thereof is liquefied by passage through cooler 70, and the liquefied portion is separated in separator 71. Uncondensed material is withdrawn from the process through line 72. Condensate separated in separator 71 is withdrawn therefrom through line 73. A portion of this condensate is returned to fractionator 56 as reflux through line 74.

The benzene fraction passing through line 65 and the xylene fraction passing through line 67 may be passed directly to reactor 6 if desired, particularly if the degree of fractionation in fractionator 56 is sufficient to produce benzene and xylene fractions of sufficient concentration. Such direct introduction of these fractions into the reaction zone may be effected through line 75, which connects line 65 with line 1, and through line 76, which connects line 67 with line 2. Preferably, however, each of the benzene and xylene fractions is first treated to extract therefrom a concentrate essentially consisting of the desired aromatic hydrocarbon. Such concentration may be effected in any suitable manner, but preferably the general method outlined above for the extraction of toluene at 59 is preferred. Consequently, line 65 is indicated as connected to a benzene extractor 59B which is generally similar in construction and operation to toluene extractor 59 and is similarly connected with a benzene stripper 61B. The benzene concentrate is withdrawn overhead from stripper 61B through line 1 which connects with mixer 4, as described above. Similarly, line 67 connects with the xylene extractor 59X which is similarly connected with a xylene stripper 61X. The xylene concentrate is withdrawn overhead from stripper 61X through line 2 which connects with mixer 4, as described above. The means provided for concentrating the toluene, benzene and xylenes are identical in the drawing, and similar reference numerals refer to similar apparatus, those applying to concentration of benzene being identified by the letter B and those applying to concentration of xylene being identified by the letter X.

The hydrocarbon mixtures withdrawn from the upper portions of extractors 59B and 59X, substantially depleted in aromatic hydrocarbons, may be recycled suitably to the aromatization process as indicated by the connection of lines 64B and 64X with line 64. Materials thus recycled through line 64 consist essentially of aliphatic hydrocarbons and may include a small proportion of naphthenes all of which are suitable for further conversion treatment for the production of aromatic hydrocarbons.

The invention has been illustrated by reference to a modification thereof involving the reaction of benzene and xylenes to form toluene. It is to be understood, however, that the invention is not thus limited but is applicable also to other reactions of highly alkylated hydrocarbons with lower-boiling hydrocarbons to produce hydrocarbons of an intermediate degree of alkylation. For example, as mentioned above, benzene may be reacted with higher-boiling aromatic hydrocarbons such as trimethyl benzenes at the same time the reaction with xylenes is effected with the formation of toluene therefrom. The invention also includes the production of alkylated hy-

drocarbons by reaction of a hydrocarbon of a lesser degree of alkylation with higher-boiling multi-ring aromatic hydrocarbons such as naphthalene, anthracene, etc.

5 The invention has been described by reference to its application in a combined process for the conversion of non-aromatic hydrocarbons to a high yield of toluene, but it is to be understood that the improved method of producing alkylated hydrocarbons by reaction of highly alkylated hydrocarbons or multi-ring aromatic hydrocarbons with hydrocarbons alkylated to a lesser degree, such as benzene in the presence of hydrogen fluoride and boron fluoride, is of general application.

15 I claim:

1. The method of producing an alkylated aromatic hydrocarbon which comprises contacting an alkylated aromatic hydrocarbon of higher molecular weight than said desired alkylated aromatic hydrocarbon and an aromatic hydrocarbon of lower molecular weight than said desired alkylated aromatic hydrocarbon at elevated temperature simultaneously with hydrogen fluoride and boron fluoride.

20 2. The method of producing an alkylated aromatic hydrocarbon which comprises contacting an alkylated aromatic hydrocarbon of higher molecular weight than said desired alkylated aromatic hydrocarbon and benzene at elevated temperature simultaneously with hydrogen fluoride and boron fluoride.

25 3. The method of producing toluene which comprises contacting xylene and benzene at elevated temperature simultaneously with hydrogen fluoride and boron fluoride.

30 4. The method of producing toluene from a mixture comprising benzene, toluene and xylenes which comprises separating toluene from the mixture and contacting remaining benzene and xylenes at elevated temperature with hydrogen fluoride and boron fluoride to produce additional toluene.

35 5. The method of producing toluene which comprises contacting xylene and benzene at a temperature of 200° to 400° F. simultaneously with hydrogen fluoride and boron fluoride.

40 6. The method of producing toluene which comprises contacting xylene and benzene at a temperature of 200° to 400° F. and at a pressure of 300 to 1000 pounds per square inch simultaneously with hydrogen fluoride and boron fluoride.

45 7. The method of producing a methylated aromatic hydrocarbon which comprises contacting an aromatic hydrocarbon more highly methylated than said desired methylated aromatic hydrocarbon and an aromatic hydrocarbon of lower molecular weight than said desired methylated aromatic hydrocarbon at elevated temperature simultaneously with hydrogen fluoride and boron fluoride.

50 8. The method of producing methylated aromatic hydrocarbons which comprises acting upon highly methylated aromatic hydrocarbons to separate methyl groups therefrom in the presence of hydrogen fluoride and boron fluoride and a hydrocarbon of lower molecular weight than said desired methylated aromatic hydrocarbons.

55 9. The method for producing xylenes which comprises contacting toluene and poly-methylated benzenes having more than two attached methyl groups at elevated temperature simultaneously with hydrogen fluoride and boron fluoride.

10. The method of producing a methylated aromatic hydrocarbon which comprises contacting a polymethylated aromatic hydrocarbon more highly methylated than said desired methylated aromatic hydrocarbon and an aromatic hydrocarbon of lower molecular weight than said desired methylated aromatic hydrocarbon at a temperature of 200 to 400° F. simultaneously with hydrogen fluoride and boron fluoride.

11. A process for converting a polyalkyl aromatic hydrocarbon to an alkyl aromatic hydrocarbon having a fewer number of alkyl groups per molecule, which comprises treating a polyalkyl aromatic hydrocarbon in admixture with a substantial molecular excess of an aromatic hydrocarbon having at least two alkyl groups per molecule fewer than said polyalkyl aromatic hydrocarbon and in the presence of hydrogen fluoride and boron fluoride to produce an alkyl aromatic hydrocarbon having fewer alkyl groups per molecule than said polyalkyl aromatic hydrocarbon, and recovering from effluents of said treatments an alkyl aromatic hydrocarbon so produced.

12. A process for converting a polymethyl aromatic hydrocarbon to a methyl aromatic hydrocarbon having a fewer number of methyl groups per molecule, which comprises treating a polymethyl aromatic hydrocarbon in admixture with a substantial molecular excess of an aromatic hydrocarbon having at least two methyl groups per molecule fewer than said polymethyl aromatic hydrocarbon and in the presence of hydrogen fluoride and boron fluoride to produce a methyl aromatic hydrocarbon having fewer methyl groups per molecule than said polymethyl aromatic hydrocarbon, and recovering from effluents of said treatment a methyl aromatic hydrocarbon so produced.

13. The method of producing a methylated aromatic hydrocarbon which comprises contacting an aromatic hydrocarbon more highly methylated than said desired methylated aromatic hydrocarbon and benzene at elevated temperature simultaneously with hydrogen fluoride and boron fluoride.

14. The method of producing methylated aromatic hydrocarbons which comprises acting upon highly methylated aromatic hydrocarbons to separate methyl groups therefrom in the presence of an aromatic of lower molecular weight than the desired methylated aromatic hydrocarbon and a catalyst comprising a liquid mixture of a major proportion of hydrogen fluoride and a minor proportion of boron fluoride.

15. The method of producing toluene which comprises contacting a higher molecular weight alkylated aromatic hydrocarbon and benzene at elevated temperature simultaneously with hydrogen fluoride and boron fluoride, said benzene being present in a substantially greater amount than said higher molecular weight aromatic hydrocarbon.

16. The method of producing an alkylated aromatic hydrocarbon which comprises contacting an alkylated aromatic hydrocarbon of higher molecular weight than said desired alkylated aromatic hydrocarbon and an aromatic hydrocarbon of lower molecular weight than said desired alkylated aromatic hydrocarbon at elevated temperature with a catalyst comprising a liquid mixture of a major proportion of hydrogen fluoride and a minor proportion of boron fluoride.

HERBERT J. PASSINO.
